Inv. No. 100

Stillman Knoughton

United States Patent Office.

STILLMAN HOUGHTON, OF WORCESTER, MASSACHUSETTS.

Design No. 5,027, dated June 20, 1871.

DESIGN FOR A DISPLAY-CARD.

The Schedule referred to in these Letters Patent and making part of the same.

To all whom it may concern:

Be it known that I, STILLMAN HOUGHTON, of the city and county of Worcester and Commonwealth of Massachusetts, have invented and produced a new and original Design for Stocking-Supporter Cards, of which the following is a specification.

The nature of my design is fully illustrated by the accompanying drawing, in which—

A B and C D represent a group of two pairs of stocking-supporters, which are folded together and placed on top of each other, their arrangement being such that the under ones extend a little beyond those above, whereby the slides or buckles *a b c d* of each are brought into full view, in the manner illustrated, while the extremities E and F of the supporters are shown hanging down loosely.

The supporters are shown in group, arranged in a lateral row across the card.

This design relates to the pictorial card itself, having a representation or picture of the goods printed upon it, and not to the arrangement of the goods upon the card.

Claim.

I claim as my invention—

The design for stocking-supporter cards, substantially as above described, and shown in the accompanying drawing.

STILLMAN HOUGHTON.
